CLEANING IMPLEMENT FOR PIANOS
OR THE LIKE

Mary M. Miley, Allentown, Pa.

Application October 19, 1934, Serial No. 749,103
Renewed April 24, 1936

6 Claims. (Cl. 15—210)

My invention relates to a cleaning implement.

An important object of my invention is to provide a device of the above mentioned character which is adapted to clean portions of a piano, such as a grand or baby grand piano, which are inaccessible for cleaning purposes by the use of the ordinary brush or mop.

A further object of the invention is to provide a cleaning device of the above mentioned character which may be readily passed between the wires of the piano for contact with the sounding board to clean the same.

A further object of the invention is to provide a device of the above mentioned character so constructed that a relatively long surface may be presented for cleaning the sounding board of the piano whereby the cleaning operation may be carried out quickly and conveniently.

A further object of the invention is to provide a device of the above mentioned character which may be employed for cleaning the wires of the piano.

Further objects and advantages of the invention will be apparent during the course of the following description.

In the accompanying drawing forming a part of this application and in which like numerals are employed to designate like parts throughout the same,

Figure 1 is a perspective view of a cleaning implement embodying my invention, showing the same in use,

Figure 2 is a central vertical longitudinal section through the cleaning implement, parts in elevation,

Figure 3 is a transverse section taken on line 3—3 of Figure 2, and,

Figure 4 is a perspective view of the flexible head of the implement.

In the drawing, wherein for the purpose of illustration is shown a preferred embodiment of my invention, the numeral 5 designates the box or body portion of a grand or baby grand piano having the horizontally disposed sounding board 6 and spaced wires or strings 7 arranged above the sounding board, as is customary.

The implement comprises a brush or mop head 8. This head includes a flexible tube 9. The tube includes oppositely arranged sides, and each side includes inner and outer elongated strips 10 and 11. These strips may be formed of any suitable flexible material, such as chamois, cloth, or the like. Arranged between the strips 10 and 11 are strands 12, extending transversely of the elongated strips. These strands are preferably formed of some soft readily foldable material, such as cotton, although other material may be used. The opposite longitudinal edges of the two pairs of elongated strips 10 and 11 are securely connected by lines of stitching 13, extend-

ing longitudinally of strips 10 and 11 throughout substantially their entire length. The strands 12 pass between the strips 10 and 11 in each pair and are securely attached to these strips by the lines of stitching 13. The fibrous strands 12 extend laterally beyond the tube 9, for substantial distances, and being highly flexible and foldable, they readily become distributed over substantially the entire surface of the tube. The forward end of the tube is preferably closed which may be effected by stitching the pairs of flexible strips 10 and 11 together and then folding them transversely so that the stitching is arranged upon the inner side of the tube. At the rear end of the tube 9, each pair of strips 10 and 11 are continued beyond the tube for a substantial distance, affording attaching extensions 14. The strips 10 and 11, at the attaching extensions are preferably glued together, although they may be secured together by any other suitable means. It is thus seen that I have provided an elongated brush or mop head of substantial length, including a tube and strands carried thereby, and the elongated brush head is readily transversely foldable or flexible.

Adapted for insertion within the flexible tube 9 and extending throughout substantially its entire length, is a bar 15, preferably formed of flat resilient material, such as spring steel. The bar 15 is elongated and has a substantial length and also has a substantial width, but is relatively thin. The bar 15 is therefore readily flexible in a direction at right angles to its surface, but is rigid in a direction parallel with its surface. In other words, when the bar is placed upon a plane horizontal surface, it may be flexed vertically but is rigid against flexing in a horizontal direction.

The rear end of the bar 15 is embedded within a shank 16, formed upon a handle 17. The numeral 18 designates a ferrule which is slotted at 19 to slidably receive the bar 15, and this ferrule is adapted to be applied to the shank 16, and is held thereon by frictional engagement. The opposite portions of the shank 16 are preferably flattened, at 20, to receive the ends of the attaching extensions 14, which are applied to the outer surface of the ferrule and folded inwardly to project into the same. The ferrule clamps these extensions to the flat faces 20. The ferrule serves to detachably connect the extensions 14 with the shank 16, and by moving the ferrule 18 forwardly it disengages the shank 16 and releases the attaching extensions 14, whereby the head 8 may be withdrawn from the rod 15, for the purpose of cleaning or repairing the same.

In use, the head 8 is applied to the bar 15 and these two elements are substantially coextensive in length and have a considerable length. The assembled head and bar are readily flexible in 60

one direction and substantially rigid in a direction at a right angle to the flexing direction. With the elements thus assembled, the head 8 may be passed between selected wires or strings 5 1 of a grand or baby grand piano, in the manner indicated in Figure 1. This will bring the brush head into engagement with the sounding board 6, as shown. If desired, substantially the entire length of the head 8 may be brought into 10 engagement with the sounding board. When in this position, the bar 15 is flexible in a vertical plane but is substantially rigid in a horizontal plane. The handle 17 may now be manipulated to shift the brush head horizontally over the 15 surface of the sounding board. It is thus seen that the portion of the brush head engaging the sounding board has a substantial length and that a large area of the sounding board is thus cleaned. The brush head is reversible and either 20 side thereof may be used. Due to the flexibility of the brush head and bar in one direction, inaccessible portions of the sounding board may be readily cleaned, and the brush head may also be inserted between the wires or strings of the 25 piano in various ways, to clean the strings. The bar is completely encased in the head and cannot contact with the surface to mar the same. The brush may be used to clean various other portions of the piano, and portions of different 30 types of pianos.

It is to be understood that the form of my invention herewith shown and described is to be taken as a preferred example of the same, and that various changes in the shape, size and 35 arrangement of parts may be resorted to without departing from the spirit of the invention or the scope of the subjoined claims.

Having thus described my invention, I claim:

1. An implement for use in cleaning pianos or 40 the like, comprising a normally generally straight elongated flexible cleaning head, an elongated bar carrying the cleaning head, said bar being flexible in one direction throughout substantially its entire length and rigid throughout substantially its entire length in a direction at substantially 45 a right angle to its flexing action, the arrangement being such that the cleaning head may be locally flexed at any point substantially between its ends and passed between the strings of the piano to engage with the sounding board beneath the strings and a handle secured to the bar.

2. An implement for use in cleaning pianos or the like, comprising a flexible elongated cleaning head including a tube and strands carried by 55 the tube, and a normally generally straight elongated bar inserted within the tube, said elongated bar being relatively thin and having a substantial width so that it is flexible in one direction throughout generally its entire length and substantially rigid in a direction at substantially 60 a right angle to its flexing movement, the arrangement being such that the head and bar may be locally flexed at any point generally between the ends thereof so that the cleaning head 65 may be passed between the strings of the piano and engage the sounding board.

3. An implement for use in cleaning pianos or the like, comprising a flexible elongated cleaning head, and a normally generally straight elongated bar extending longitudinally of the cleaning head throughout substantially the entire length of the cleaning head and secured thereto, said bar being resilient and flexible in one direction 70 throughout generally its entire length and

substantially rigid in a direction at substantially a right angle to the direction of flexing of the bar, the arrangement being such that the head and bar may be locally flexed at any point generally between the ends thereof so that the cleaning head may be passed between the strings of the piano and a considerable portion of its length brought into engagement with the sounding board, the tension of the flexed resilient bar holding the cleaning head in proper frictional engagement with the sounding board. 5

4. An implement for use in cleaning pianos or the like, comprising a flexible elongated cleaning head having a substantial length and including a tube and strands carried thereby, an elongated bar inserted within the tube and extending throughout substantially the entire length of the tube, said bar being resilient and flexible throughout generally its entire length in one direction and substantially rigid in a direction at 20 substantially a right angle to the direction of flexing of the bar, and a handle secured to the bar, said elongated bar being a great deal longer than the handle, the cleaning head and bar being locally flexible at any point generally between the ends so that the same may be passed between the strings of the piano and contact with the sounding board, the flexing of the resilient elongated bar serving to hold the cleaning head in proper frictional engagement with 30 the sounding board. 15

5. An implement for use in cleaning pianos or the like, comprising a flexible elongated cleaning head, and a normally generally straight solid resilient bar which is so slender that it may be 35 readily passed between the strings of the piano in spaced relation from such strings, said solid resilient bar extending longitudinally of the cleaning head throughout substantially the entire length of the cleaning head and secured 40 thereto, the arrangement being such that the cleaning head and solid bar may be locally flexed at any point generally between the ends thereof so that the cleaning head may be passed between the strings of the piano and a considerable portion of its length brought into engagement with the sounding board, the tension of the flexed solid resilient bar holding the cleaning head in proper frictional engagement with the sounding board. 45

6. An implement for use in cleaning pianos or the like, comprising an elongated flexible cleaning head including a tube, said tube including sides, each side including a pair of strips, fibrous strands arranged between the strips in each pair and extending transversely thereof, lines of stitching attaching the pairs of strips, the strips having extensions at their rear ends projecting beyond the lines of stitching, an elongated bar for insertion within the tube and extending 55 throughout substantially the entire length of the tube, said elongated bar being resilient throughout substantially its entire length in one direction and substantially rigid in a direction at substantially a right angle to its flexing action, a 60 handle having a reduced shank secured to the rear end of the bar, said handle being a great deal shorter than the bar, a ferrule slideable upon the bar and adapted to have the extensions folded inwardly about the same, the ferrule and extensions being adapted for insertion upon the reduced shank to thereby attach the extension to the handle. 65
